UNITED STATES PATENT OFFICE.

ANDREW H. CANDEE, OF FOREST HILLS, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed November 20, 1920. Serial No. 425,391.

To all whom it may concern:

Be it known that I, ANDREW H. CANDEE, a citizen of the United States, and a resident of Forest Hills, in the county of Allegheny and State of Pennsylvania, have invented a new and useful Improvement in Systems of Control, of which the following is a specification.

My invention relates to systems of control and it has special relation to the control of a plurality of motors that are adapted to be operated in either series or parallel relation.

One object of my invention is to simplify the apparatus and circuits for operating motors in either series or parallel relation.

Another object of my invention is to connect the actuating coil for the main-line contactor directly between the series-parallel controller and the reversing controller, thereby interlocking the two controllers to avoid the danger of improperly energizing the motors.

Other and more specific objects of my invention will be apparent from the following description and claims.

Inasmuch as the main-circuit connections and apparatus for operating a plurality of motors in series or in parallel relation are now well known, as well as the main-circuit connections for effecting a reversal of the motors, no detailed illustration thereof or reference thereto will be made in this application.

For the purposes of the present invention, it will suffice to say that it is highly desirable to interlock the respective actuating means for controlling the above-mentioned operations in such manner that there shall be no possibility of reversing the current in the motors at a time when it would be damaging to do so.

The present invention accomplishes the above-mentioned result with the smallest number of control fingers and contact segments compatible with efficient operation.

My invention will best be understood by reference to the accompanying drawing, wherein the single figure is a diagrammatic view of as much of the apparatus and circuits embodying my invention as will be necessary for a complete understanding thereof.

Referring to the drawing, the system here shown comprises suitable supply-circuit conductors "trolley" and "ground," a main-

motor circuit 10, as indicated by the legend 55 "To motors," a series-parallel drum 1 and a reversing drum 7, both of the electromagnetically governed type, a control switch 4 and a master-reverser 6 for governing the operation of said drums, a line switch or 60 main-line contactor 5, which is connected in the main circuit 10, and a control resistor 11 for supplying suitable low voltage to the various illustrated actuating coils.

The series-parallel drum and the reversing 65 drum are shown in part and are appropriately designated by the legends appearing upon the drawing. In practice, these drums are preferably incorporated in a single motor controller. The series-parallel 70 controller 1 is shown as equipped with two contact segments. Appropriate means for moving the drum to either series or parallel position, whereby the motors will be operated accordingly, is here shown as electromagnets 2 and 3. The contact segments of the drum 1 are shown engaging one control finger in circuit with the "series" coil 2, one control finger in circuit with a source of energy, one control finger in circuit with 80 the "parallel" coil 3, and one control finger in circuit with the coil of a main-line contactor 5. There are, in addition, two auxiliary control fingers that are connected to the opposite switch jaws of the knife-blade 85 switch 4. The blade of the switch 4 is shown as pivoted so as to be movable to engage either of said jaws, and has a connection direct to the ground.

In the "series" position S of the drum 1 90 in the drawings, the series coil has been energized, thus pulling the drum to the position shown. This has been accomplished by manipulation of the movable knife-blade switch 4 which, in the full-line position 95 shown, will operate the motors in series relation.

The contact segments of the drum 1 are so shaped that, in the position shown, the parallel coil 3 is ready to be energized whenever the movable blade of the switch 4 engages the opposite switch jaw. When this blade is moved to the dotted-line position in the drawing, the drum will be moved to the "parallel" position designated by the letter 100 P, wherein the motors will run in parallel relation, and the control finger of the series coil will be engaged ready to energize this

coil when the switch 4 is properly moved. It will be noted that, in both the series and the parallel positions, the coil of the main-line contactor 5 is connected to the ground, 5 through one of the auxiliary control fingers, the switch jaw that is engaged by the blade of the switch 4, and said blade, which, it will be remembered, is connected directly to the ground.

10 The apparatus for controlling the reversing of the motors is of the same general type as that just described for the series-parallel controller; namely, the drum 7 is shown as equipped with two contact segments, and 15 electromagnets 8 and 9 for effecting "forward" and "reverse" operations, corresponding to positions F and R, respectively. The contact segments are adapted to engage two control fingers that are respectively connected to the coils 8 and 9, two control fingers in circuit with the coil of the contactor 5 and two control fingers in circuit with control fingers of a master reverser 6, conventionally shown in the drawing.

20 25 The master reverser is shown in the forward position F. Accordingly, the coil of the electromagnet 8 has been energized to move the drum 7 to the forward position, designated by the letter F. Should the master reverser 6 be moved to the opposite position r, the coil of the reversing electromagnet 9 would be energized to move the drum 7 to the position designated by the letter R. It will be noted that the coils 8 and 9 are 30 35 connected directly to the ground, this ground connection being the one common to the movable element of the knife-blade switch 4.

The direct connection of the main-line contactor between the two drums 1 and 7 40 enables these controllers to be so interlocked that the motors controlled thereby cannot be operated in harmful relation.

This may best be understood if the invention is regarded as applied to a railway car 45 having a complete motor-controller at each end of the car. In this event, there would be two of the knife-blade switches 4, one at each end of the car. It may be assumed that the controller at the front end of the car has 50 been left in the position shown in the drawing, namely, forward, series position. The motorman could not go to the other end of the car and operate the motors in the reverse direction, either in series or parallel relation, until the master reverser 6 had been 55 actuated to move the drum 7 to the "reverse" position.

This simplified interlocking arrangement is accomplished by reason of the fact that 60 the actuating coil of the main-line contactor 5 is connected directly between the two drums 1 and 7. Accordingly, there is but a single circuit therebetween.

From the foregoing description, it will be 65 apparent that a reduction in the necessary

apparatus, as well as a reduction in circuits, is accomplished by the present invention, thereby diminishing the cost of production and installation of a control system of the type set forth.

70

I do not wish to be restricted to the specific circuit connections, or apparatus, or arrangements of parts herein set forth, as various modifications thereof may be made without departing from the spirit and scope 75 of my invention. I desire, therefore, that only such limitations shall be imposed as are indicated by the appended claims.

I claim as my invention:—

1. In a control system for a plurality of 80 motors, the combination with a main-line contactor and a controller which, when operated to one position, connects said motors in series relation and, when operated to another position, connects said motors in parallel relation, of a second controller adapted 85 to reverse the current in said motors, both of said controllers being in circuit with a certain element of said contactor.

2. In a control system for a plurality of 90 motors, the combination with a source of energy, control means for reversing said motors and a main-line contactor, the control circuit of which is in circuit therewith, of 95 plural-position control means adapted to connect said motors either in series relation or in parallel relation, said last-named means employing two fingers respectively operative in only one of the positions corresponding to 100 said relations, a finger in circuit with said source of energy, and a finger in circuit with the coil of said main-line contactor, whereby a reduced number of contact members is 105 employed for interlocking the two control means.

3. In a control system for a plurality of 110 motors, the combination with a main-line contactor, control means for reversing said motors, and control means for connecting 115 said motors in series or in parallel relation, 120 of the actuating coil of said main-line contactor being connected between said control means to interlock them against improper running connection.

4. In a control system for a plurality of 115 motors, the combination with means for reversing said motors, of control means for connecting said motors in series or in parallel relation, said means including a switch 120 for controlling said series-parallel connections, said switch being located upon the negative side of said control means.

5. In a control system for a plurality of 125 motors, the combination with a plurality of switching devices for governing different operations of said motors, of a line switch coil connected between said devices.

6. In a control system for a plurality of 130 motors, the combination with a source of energy, a main-line contactor, and means for

- reversing said motors employing two control fingers in circuit with the control circuit of said main-line contactor, two control fingers in circuit with said source of energy, and two control fingers respectively operative in only one of the forward and the reverse connections, of means for connecting said motors in series or in parallel relation, said control means embodying only two fingers respectively operative in only one of the positions corresponding to said relations, a finger in circuit with said source of energy, and a finger in circuit with the coil of said main-line contactor.
7. In a control system for a plurality of 15 motors, the combination with a plurality of control drums for governing different operations of said motors, of a main-circuit switch having an actuating coil constituting the sole connection between said drums. 20

In testimony whereof, I have hereunto subscribed my name this 12th day of November 1920.

ANDREW H. CANDEE.
